UNITED STATES PATENT OFFICE.

GEORGE BORST, OF ROCHESTER, NEW YORK.

MATCH-BOX.

No. 830,406.

Specification of Letters Patent.

Patented Sept. 4, 1906.

Application filed November 11, 1905. Serial No. 286,885.

To all whom it may concern:

Be it known that I, GEORGE BORST, a citizen of the United States, residing at Rochester, in the county of Monroe and State of New York, have invented new and useful Improvements in Match-Boxes, of which the following is a specification.

This invention relates to match-boxes designed especially for application as a lamp attachment, and has for its objects to produce a comparatively simple inexpensive device of this character which may be readily installed for use, one which will when in closed position be practically invisible, thus to obviate marring the appearance of the lamp, and one wherein the box may be conveniently locked in closed position or released and moved to open position when circumstances require, a simple means being provided for limiting the opening movement of the box.

With these and other objects in view the invention comprises the novel features of construction and combination of parts more fully hereinafter described.

In the accompanying drawings, Figure 1 is an elevation of a portion of a lamp equipped with a match-box embodying the invention. Fig. 2 is a detail sectional view, the section being taken on the line 2-2 of Fig. 1. Fig. 3 is a detail section taken centrally and longitudinally through the box. Fig. 4 is a transverse section taken on the line 3-3 of Fig. 2. Fig. 5 is a front elevation of an automobile-lamp equipped with a match-box embodying the invention.

Referring to the drawings, 1 designates a lamp having a stand or support 2, provided with a hollow base 3, in which is fixed a horizontal supporting-plate 4, on which is slidably disposed a match box or receptacle 5, the front wall 6 of which is shaped to conform to the configuration of the base 3 and to present in appearance an integral part thereof, there being provided at spaced intervals around the base radially-projecting ornamental knobs 7, while rotatively mounted in the wall 6 is a finger-piece or knob 8, corresponding to and simulating the knobs 7.

Formed upon the side edges of the supporting-plate 4 are vertically-uprising bearing portions or flanges 9, terminating at their upper ends in inturned engaging portions or flanges 10, designed to bear upon the upper edges of the adjacent walls of the receptacle, there being also formed upon the supporting-

plate and at its rear edge a vertical bearing portion or lug 11, constituting a stop or abutment with which the box 5 contacts when in closed position to limit its inward movement.

Fixed upon the inner end of the knob 8 and for movement therewith is a locking member or button 12, adapted to engage the base 3 for locking the match-receptacle in closed position, it being apparent that the member 12 may be readily moved to releasing position 65 by a partial rotation of the knob 8, thus permitting the box to be freely moved to open position.

In Fig. 5 the box 5 is shown applied to the base of an automobile-lamp, the construction and operation of the parts being identical with those above described with the exception of such slight changes in the form of the box as are necessary to adapt it for application to the lamp-base 13.

From the foregoing it is apparent that I produce a simple device admirably adapted for the attainment of the ends in view, it being understood that in attaining these ends minor changes in the details herein set forth 80 may be resorted to without departing from the spirit of the invention.

Having thus described my invention, what I claim is—

1. In a device of the class described, a lamp having a base, a supporting-plate sustained within the base and having at its inner end an upturned stop-flange, a match-receptacle movably disposed upon said plate to move outward through an opening in the base, uprising flanges provided on the plate and having engaging portions adapted to bear on the upper edges of the adjacent walls of the receptacle, the rear wall of the latter being adapted for contact with the stop-flange to limit the inward movement of the receptacle and with its front wall flush with the adjacent wall of the base, knobs attached to and radiating from the base, a finger-knob rotatively disposed in the front wall of the receptacle, said knob being made in imitation of the first-named knobs, and a locking-button fixed for movement with the rotary knob and adapted for engagement with the base to lock the receptacle in closed position.

2. In a device of the class described, a lamp having a base, a supporting-plate sustained within the base and having at its inner end an upturned stop-flange, a match-receptacle movably disposed upon said plate to

2
move outward through an opening in the base, uprising flanges provided on the plate and having engaging portions adapted to bear on the upper edges of the adjacent walls of the receptacle, the rear wall of the latter being adapted for contact with the stop-flange to limit the inward movement of the receptacle and with its front wall flush with the adjacent wall of the base, a finger-knob rotatively mounted in the front wall of the receptacle, and a locking-button fixed for

movement with the rotary knob and adapted for engagement with the base to lock the receptacle in closed position.

In testimony whereof I affix my signature 15 in presence of witnesses.

GEORGE BORST.
